UNITED STATES PATENT OFFICE.

JOSEPH SYLVAN, OF CHICAGO, ILLINOIS.

VENTILATOR.

Application filed November 4, 1920. Serial No. 421,625.

To all whom it may concern:

Be it known that I, JOSEPH SYLVAN, a citizen of the United States, and a resident of Chicago, in the county of Cook and State of Illinois, have invented certain new and useful Improvements in Ventilators; and I do hereby declare that the following is a full, clear, and exact description thereof, reference being had to the accompanying drawings, and to the letters of reference marked thereon, which form a part of this specification.

This invention relates to improvements in ventilators for roofs, skylights and the like, and consists in the matters hereinafter described and more particularly pointed out in the appended claims.

The object of the invention is to improve the construction and operation of that type of ventilator illustrated and described in my copending application for patent, filed April 29, 1920, and bearing Serial Number 377,474.

The many advantages of the invention will more fully appear as I proceed with my specification.

In the drawings:—

Figure 1 is a vertical transverse section through a skylight, to which my improved ventilator has been applied.

Figure 2 is a view on an enlarged scale of the parts at the top of Figure 1, with several of said parts in a changed position.

Figure 3 is a view similar to Figure 2 with several of the parts in another changed position.

Figure 4 is a view of parts shown in the left hand side of Figure 3, with said parts in a still further changed position.

Figure 5 is a horizontal detail section taken on the line 5—5 of Figure 2.

Figure 6 is a vertical detail section, taken on the line 6—6 of Figure 2.

Figure 7 is a detail view in elevation of a post or upright, embodied in my invention.

Figure 8 is a horizontal detail section taken on the line 8—8 of Figure 2.

Figure 9 is a detail view in elevation of a hinge block which will be more specifically referred to later.

Referring now in detail to that embodiment of the invention illustrated in the accompanying drawings:—15 indicates the

gabled skylight of a building to which my improved ventilator construction has been applied. Said skylight which may be of any desired length, includes longitudinally spaced, transversely extending horizontal beams 16, which rest at their ends on the skylight curbs 17, standards 18 arising from said beams along the median line of the skylight, and rafters 19 which are fixed to said standards at about their middle and to the ends of the beams. Said rafters are inclined downwardly and outwardly from each other from said standards to provide the pitch for the skylight. Preferably all of said parts are made of angle bars. Connecting the rafters 19 are longitudinally extending angle bars 20, which are spaced equidistant on each side of the standards 18, and secured to said angle bars are the inner ends of smaller inverted T bars 21 arranged parallel with the rafters 19, to provide the necessary support for the skylight panels 22. Said panels are made of any suitable material, permitting the entrance of light. The angle bars 20 and the panels 22, together with upright triangular plates 23 at the ends of the skylight, define a rectangular opening 24, at the ridge or peak of said skylight. The outer ends of the inverted T bars 21, are connected together by longitudinal angle bars 25, arranged near the outer top corners of the curbs 17, and gutter strips 26 connect said bars with the curbs and act to catch such vapor as condenses on the under side of the panels and discharge it at the ends of the skylight.

Each standard 18 is built up of the transversely spaced, oppositely facing angle bars 27—27 which are riveted or otherwise secured at their bottom ends to the beams 16. The top ends of the transverse flanges of said angle bars are beveled off as shown in Figure 7 and secured to the other opposed flanges at the top end of said bars, and extending beyond the top thereof are inverted U-shaped straps 28, each having a filler block 29, between its legs, the said flanges, straps and blocks being riveted together. The top ends of said straps and filler blocks are formed to provide a support for a longitudinal shaft 30 which extends the full length of the skylight. Between said angle

- bars 27, and coating with the bottom ends of the straps 28 and filler blocks 29, are shorter filler blocks 31 which provide a bearing for a second longitudinal shaft 32, which also extends the full length of the skylight. Said shorter filler blocks extend a suitable distance outwardly beyond the face of the transverse flanges of the angle bars 27 to act as stops, as will appear later.
- 10 To the outer faces of the transverse flanges of said angle bars 27, near their bottom ends, are secured plates 33, each of which has a hole 34 to provide a bearing for a third longitudinal shaft 35, which also extends the full length of the skylight. Secured to the inner opposed flanges of the angle bars 27, and extending between the filler blocks 31 and plates 33, are guide strips 36, the upright exposed margins of which terminate short of the outer ends of the filler blocks 31 as shown in Figure 6 so that said blocks overhang said guide strips. The bottom ends of said strips are spread apart as shown at 37 in Figure 7.
- 15 Reference numerals 38—39 indicate similar, longitudinal sections or frames which are pivotally connected to the shaft 30 so as to swing in a vertical plane. Said sections are of a length equal to the distance between the end plates 23 of the skylight, and are of a combined width so as to overhang the angle bars 20 and the inner top ends of the panels 22 defining the sides of the skylight opening 24, when said sections are 20 in either open or closed positions, see Figures 1 and 2.
- 20 Each frame is built up of inner and outer, oppositely facing, longitudinally extending angle bars 40 and 41, which are connected together in the proper spaced relation by means of transverse connecting members 42 made of inverted T bars. Secured to the horizontal flanges of the T bars are glass panels 43, there being of course the usual water tight connection between said bars and panels.
- 25 The flanges of the angle bars 40, arranged parallel with the panel, have secured to them, hinge straps 44 which embrace and have pivotal bearing on the shaft 30. Preferably these straps are arranged, one on each side of a standard 18, pins 45 (see Figure 6) passing through the shaft at the ends of said straps, locking said straps against endwise movement on said shaft. Each strap includes a filler block 46 to add strength and rigidity thereto as shown in Figure 9. When the sections 38 and 39 are in their normal closed position, the angle bars 40 rest upon the beveled top end of the angle bars 27 forming the uprights 18.
- 30 Means are provided to close the gap between the spaced, adjacent margins of the sections against the entrance of rain, snow or dust, no matter what the relative inclina-
- tion may be between said sections and such means are as follows: 47—48 indicate thin sheet metal sealing strips, the outer margins of which are bent to provide longitudinal loops 49 that overhang the inner margins 70 of the panels 43. The middle portions of said strips extend over and beyond the top edge of the substantially upright flanges of the angle bars 40, and the inner margins 50, of said strips, are transversely curved 75 so that one overlaps the other to provide for the maximum amount of swinging movement of the sections 38—39. A flexible weather-proof ridge strip 51, which encloses or covers the strips 47—48, is secured at 80 its margins, between the inner margins of the panels and the parallel flanges of the angle bars 40. The ridge strip 51 fits snugly over the sealing strips when both sections 38—39 are in their closed positions as shown 85 in Figure 1, but will flex or buckle to provide for the movement between said sections. This ridge strip may be of any flexible waterproof material such a sheet lead or even prepared roofing, and to prevent the cutting of the same by the edges of the panels, I provide a protecting strip 52 which binds the edges of the panels so that direct contact with said ridge strip is avoided. 90
- 95 To the inner surfaces of the angle bars 41, at the outer ends of the sections 38—39, is secured a sheet metal gutter strip 53, which is so formed as to catch the water of condensation from the panels 43, and discharge the same at the ends thereof. Said gutter strips each include an inverted channel 54 which engages about the top edges of the angle bars 20 of the skylight and prevents the entrance of rain, snow, or dust into the 100 opening 24 when the said sections are in their closed positions.
- 105 Means are provided for swinging the sections into open position, either simultaneously or independently of one another so that the wind may blow over the opening 24 in one case, or over the outer margin of either section 38—39, in the other case, to establish a suction up through said opening and properly ventilate the entire room of 110 the building beneath the skylight. Such means are as follows: 55—55 indicate links of a suitable length arranged in pairs, there being one pair of such links for each upright 18, used in the skylight. The outer 115 ends of each pair of links are pivotally connected to brackets 56 fixed to the T bars 42 near their outer ends, the inner end of the links being pivotally connected together as at 57. The pivots 57 each include a roller 120 58 and an eye 58^a. The rollers are adapted in one instance to have a guided movement between the guide strips 36 of the uprights 18, and the eyes 58^a (see Figure 6) have secured to them the like ends of chains 59. 125 130

- The other ends of said chains are wound about and are fixed to the shaft 32 before mentioned. A pulley 60 is also secured to said shaft between its ends, and associated with and trained over said pulley is an actuating chain 61 which hangs down in a loop within convenient reach of the person desiring to operate the same. When both sections are in the closed position shown in 5 Figure 1, and neither section is locked in this position as will hereinafter be described, the roller 58 will occupy a position below but in line with the guide space between the plates 36. A pull on the chain 61 will 10 rotate the shaft 32, and wind up all the chains 59 thereon, the rollers 58 entering the guide passageway between the plates 36 until the inner ends of the links engage the projecting ends of the blocks 31, and stops 15 there. As the inner ends of the links are thus raised, they will impart an upward swinging movement to both sections simultaneously, into a position inclined slightly downwardly from the horizontal plane of 20 the axis of the shaft 30. With the sections in this position as shown in Figure 2, or in any position intermediate the full closed and full opened position, the parts are so proportioned that their weight will not 25 cause them to fall into a closed position. Thus the atmospheric air may pass beneath the sections and over the top of the opening in the skylight to provide the necessary ventilation.
- 30 Should it be desired to open only one section and not the other, I provide a means which may be actuated to lock either section, so that the unlocked section may be opened by the chain 61.
- 35 Fixed at desirable points on the shaft 35, preferably near each standard 18, is a locking bar 62, the top end of which is bent to provide the oppositely disposed hooks 63—63 which carry an inverted V-shaped cap piece 40 100
- 40 Said bars are fixed at their bottom ends to the shaft 35, and are of such length that the hooks 63 and cap piece 64, normally overhang the top edges of one or the other of the angle bars 20, the margin of one hook 45 substantially entering the gutter provided 105
- 45 by the strip 53 on the angle bars 41 at the outer end of each section. Fixed to about the middle of the shaft 35 is a loop 65 which extends in a direction opposite the bar 62, and from said loop depends a chain 66 (see 50 110
- 50 Figure 1) which may be pulled to rock the shaft and thus swing the locking bar from one side to the other to lock the desired section.
- 55 In Figure 1 the locking bar is shown as 115
- 55 engaging the section 39. If it is desired to open this particular section, the chain 66 is actuated to swing the locking bars into the position shown in dotted lines in said 60 120
- 60 Figure 1. A pull on the left hand side lap 125
- 65 of the chain 61 will rotate the shaft 32 in a counter clockwise direction, and will wind up the chains 59 thereon. This will tend to pull the inner ends of the links upwardly, but as the section 38 is locked, the roller 70
- 70 can not enter the guide passageway between the plates 36, as the inner ends of the links will swing about the pivotal connections with the section 38 and thus away from said 75
- 75 passageway. As the chains 59 are further wound about the shaft, the links will tend to straighten out, with the result that section 39 is swung into its full open position wherein it will extend in a plane inclined 80
- 80 upwardly from the horizontal axis of the shaft 30. Thus, with the wind blowing upon the closed section, a part of the same will be deflected by the top surface of the open section, and as it passes over the outer margins of the open section, it will produce a 85
- 85 partial vacuum beneath said margin, and thus establish a suction up through the opening 24 in the skylight. To close said section, a pull is imparted to the right hand lap of the chain. 90
- 90 Should it be desired to open the section 38, the locking bars 62 are moved into locking engagement with the section 39, when a pull on the left hand lap of the chain will 95
- 95 open the section 38 in the manner above described.
- When both sections are in their open position, and it is desired to again close the same, it is immaterial on which side the locking bar is positioned, because in the 100
- 100 closing movement of the sections, the gutter strip 53 will engage the cap piece 64 of said locking bar, and by reason of the inclination thereof, will push the same inwardly as shown in Figure 4, until said strip passes 105
- 105 said cap piece. To properly adjust the normal locking positions of the locking bar with reference to the gutter strips on the outer margins of the sections, I provide stop pins 67 in said bars near their hooked ends, 110
- 110 which stop pins engage against the angle bars 20. Preferably these stop pins are threaded through said bars and have associated nuts for locking them in their adjusted position. 115
- 115 It is apparent that my improved ventilator construction possesses many advantages. One or the other section may be opened to provide the desired suction above the skylight opening, according to which way the 120
- 120 wind is blowing. A one piece ridge strip of flexible material is used so that it is impossible for rain or snow to enter through the space between the inner ends of the said sections.
- Furthermore, should both sections be in their closed position, and an excessive air pressure be built up for any reason, in the room beneath the skylight, said pressure will lift the unlocked section and thus pass 130

out through the opening 24 to the atmosphere, without blowing out the panels of the skylight as occurs when both sections are held in some manner in a closed position.

5 While in describing my invention, I have referred to certain details of mechanical construction and arrangement of parts, I do not wish to be limited thereto except as may be pointed out in the appended claims.

10 I claim as my invention:—

15 1. A ventilator of the kind described, comprising in combination with means providing a ventilation opening, a pair of oppositely arranged, angularly disposed sections normally closing said opening, a shaft spaced above said opening, means pivotally connecting the adjacent inner margins of said sections to said shaft, so that said sections are capable of a swinging movement about said shaft away from and toward said opening, means for normally locking either section in its closed position, and operating means common to both sections for swinging the unlocked section into its open position.

20 25 2. A ventilator of the kind described, comprising in combination with means providing a ventilation opening, a pair of oppositely arranged, angularly disposed sections normally closing said opening, a shaft spaced above said opening, means pivotally connecting the adjacent inner margins of said sections to said shaft, so that said sections are capable of a swinging movement about said shaft away from and toward said opening, means for normally locking either section in its closed position, said means being capable of being actuated so as to release both sections, and operating means common to both sections for swinging them into their open position when said locking means is in a position permitting such movement.

30 35 3. A ventilator of the kind described, comprising in combination with means providing a ventilation opening, a shaft spaced above and extending longitudinally of said opening, sections pivoted at their adjacent margins to said shaft, to swing in a vertical plane to open and close said opening, a swinging bar pivoted in a plane below said shaft for engaging and locking either section in a position closing said opening, and actuating means common to both sections to swing them into open and closed positions, said means when one section is in its locked closed position, acting to open the other section.

40 45 50 55 60 65 4. A ventilator of the kind described, comprising in combination with means providing an elongated ventilation opening, a shaft spaced above and extending longitudinally of said opening, sections pivoted at their adjacent margins to said shaft, to swing in a vertical plane to open and close said opening, a rock shaft parallel with but

below the first mentioned shaft, a locking bar on said shaft, said bar including hooks adapted to engage the outer margins of either section, and means acting to open both sections simultaneously when said hooks are disengaged therefrom.

5. A ventilator of the kind described comprising in combination with means providing a ventilation opening, standards rising in the median line of said opening, a shaft 75 journalled in the top ends of said standards, sections pivoted on said shaft and capable of a swinging movement to open and close said opening, links pivoted at their outer ends to said sections and at their inner ends, 80 to each other, actuating means connected to the inner ends of said links, and means on said standards for guiding the inner ends of said links when said actuating means are operated.

6. A ventilator of the kind described, comprising in combination with means providing a ventilation opening, standards arising in the median line of said opening, a shaft journalled in the top ends of said standards, 90 sections pivoted on said shaft and capable of a swinging movement to open and close said opening, links pivoted at their outer ends to said sections and at their inner ends to each other, actuating chains connected 95 to the inner ends of said links, means on said standards for guiding the inner ends of said links when said actuating chains are operated, and means on said standards limiting the upward movement of the inner ends of 100 said links with respect to said guiding means.

7. A ventilator of the kind described, comprising in combination with means providing an elongated ventilation opening, 105 standards arising in the median line of said opening, a shaft journalled in the top ends of said standards, sections pivoted on said shaft, and capable of a swinging movement to open and close said opening, links pivoted 110 at their outer ends to said sections and at their inner ends to each other, a roller associated with the inner ends of said links, operating chains also secured to said inner ends of said links, guide strips on said standard 115 to receive the roller, and a stop on said standard at the top ends of said guide strips.

8. A ventilator of the kind described, comprising in combination with means providing a ventilation opening, a horizontally 120 extending shaft, ventilator sections one on each side of said shaft and including inner and outer marginal angle bars, straps secured to said inner angle bars and having loops passing about the shaft, and means 125 for actuating said sections to swing them about said shaft, one at a time or both together, said parts being so constructed that when both sections are swung together they will stand in a position inclined downwardly 130

from the horizontal plane of the axis of said shaft, but when only one section is swung into a full open position, said section will stand in a position inclined upwardly from the horizontal plane of the axis of said shaft.

5 In testimony that I claim the foregoing as my invention, I affix my signature in the

presence of two witnesses, this 29th day of October, A. D. 1920.

JOSEPH SYLVAN.
